(57) **CLAIM**

The ornamental design for a top of spray can, as shown and described.

DESCRIPTION

FIG. 1 is an upper front perspective view of a top of spray can in accordance with one embodiment of the present invention;

FIG. 2 is an upper rear perspective view of the top of spray can of FIG. 1;

FIG. 3 is a front elevation view of the top of spray can of FIG. 1;

FIG. 4 is a rear elevation view of the top of spray can of FIG. 1;

FIG. 5 is a left side elevation view of the top of spray can of FIG. 1, the right side elevation view being a mirror image thereof;

FIG. 6 is a top plan view of the top of spray can of FIG. 1;

FIG. 7 is a bottom plan view of the top of spray can of FIG. 1;
FIG. 8 is an upper front perspective view of a top of spray can in accordance with another embodiment of the present invention;

FIG. 9 is an upper rear perspective view of the top of spray can of FIG. 8;

FIG. 10 is a front elevation view of the top of spray can of FIG. 8;

FIG. 11 is a rear elevation view of the top of spray can of FIG. 8;

FIG. 12 is a right side elevation view of the top of spray can of FIG. 8, the right side elevation view being a mirror image thereof;

FIG. 13 is a top plan view of the top of spray can of FIG. 8; and,

FIG. 14 is a bottom plan view of the top of spray can of FIG. 8.

The broken lines immediately adjacent the shaded areas represent the bounds of the claimed design while other broken lines are directed to environment and are for illustrative purposes only; features illustrated in broken lines form no part of the claimed design.
